UNITED STATES PATENT OFFICE.

THEODOR WENSEL, OF JOLIET, ILLINOIS.

PRINTING-PRESS.

1,148,470.

Specification of Letters Patent. Patented July 27, 1915.

Application filed June 24, 1912. Serial No. 705,676.

To all whom it may concern:

Be it known that I, THEODOR WENSEL, a citizen of the United States, and resident of Joliet, Illinois, have invented certain new and useful Improvements in Printing-Presses, of which the following is a specification.

My invention relates generally to a printing press for producing illustrations and more specifically defined it relates to a press for reproducing artistic prints or pictures from printing plates.

The object of my invention is to provide a printing press wherewith more artistic prints can be obtained from a given plate than is possible with the printing presses hitherto devised.

A further object of my invention is to provide a printing press for carrying out the improvements in the process of printing which are described and claimed in my companion application filed of even date herewith entitled Process of producing illustrations, Serial No. 705,678.

My invention consists generally in a printing press having a reciprocating type carrying bed, a transfer cylinder mounted for rotation over the bed, means for lowering and raising same to contact and to free the type, an impression cylinder operating in unison with the transfer cylinder, and means for moving the impression cylinder to and from the transfer cylinder.

My invention consists further in a printing press having a reciprocating type bed, a two revolution impression cylinder mounted over the type bed, means for moving the transfer cylinder into ink selecting relation to the type and an impression cylinder adapted to present paper to the transfer cylinder under pressure.

My invention also resides in a printing press having a reciprocating flat type bed, means for inking the type, an undulatory-surfaced transfer cylinder mounted over the reciprocating bed, an undulatory-surfaced impression cylinder connected to the transfer cylinder, means for lowering and raising the transfer cylinder, and means for moving the impression cylinder to and from the transfer cylinder for purpose of feeding paper thereto under pressure.

My invention resides further in a printing press having a reciprocating flat type bed, a rubber covered undulatory surfaced transfer cylinder mounted over the type

bed, a rubber covered undulatory surfaced impression cylinder operatively connected for rotation with the transfer cylinder, means for depressing the transfer cylinder to contact the type when moving in one direction, means for moving the impression cylinder toward the transfer cylinder to present paper thereto under pressure, and means operating to retract the impression cylinder and to raise the transfer cylinder.

My invention also resides in a printing press comprising a flat reciprocating bed, a plate receiving portion thereof adapted for the adjustable arrangement of printing plates, means for inking the printing plates, a two-revolution transfer cylinder mounted over the type bed, means for pressing the transfer cylinder against the type as it moves in one direction, an impression cylinder operatively connected to said transfer cylinder and having means for forcibly presenting paper to the transfer cylinder.

My invention consists further in the arrangement, construction and combination of parts whereby the aforesigned objects as well as other objects which will hereinafter appear are attained. It will be more readily understood by reference to the accompanying drawings which illustrate a preferred embodiment thereof and in which:

Figures 1 and 1^a read together represent a side elevation of a printing press embodying my invention; Fig. 2 is a side elevation of that portion of the machine which carries the printing cylinders viewed from the side opposite to that shown in Figs. 1 and 1^a; certain gearing and other parts being removed to disclose the cylinder operating mechanism more clearly; Fig. 3 is a vertical cross section viewed substantially from the lines 3-3 of Figs. 1 and 2; Fig. 4 is a top plan view of the printing cylinders and a portion of the type bed; and Figs. 5 to 8, inclusive, are diagrammatic views depicting different relative positions of the type bed, transfer cylinder, and impression cylinder.

The class of printing press upon which my invention is an improvement is known as "flat bed" printing presses. It derives its name from the type bed, which is flat and on which the type form or printing plates are arranged. In such presses a single impression cylinder is mounted over the bed and it feeds paper to the type as the type moves in one direction and then rises to permit free return of the type. A print is

thereby made for every reciprocation of the type bed or for every other revolution of the impression cylinder. For this reason such presses are sometimes known as "two revolution presses."

Now referring to the drawings I shall describe my invention which may also be termed a "flat bed" or "two revolution press", because it has a flat reciprocating bed upon which the printing plates are mounted and because it produces a print for every reciprocation of the type bed. But, as will appear more fully hereinafter, I provide two cylinders instead of one, and I do not press the paper against the type as is done in the "flat bed" presses now in general use. The flat bed 2 comprises a lower portion 2' upon which the type or printing plates 3 are mounted and a raised portion 4, which is "type high", and which serves as an ink conveyer. The ink conveyer 4 receives ink from a fountain and rolls 5 at the forward end and carries it to distributing rolls 6 from which it is evenly applied to the printing plates 3 as they pass thereunder. The type bed reciprocates from front to rear sliding on a runway 6', which is suitably supported in the main frame A of the machine. Rollers 7 are interposed between the runway and type bed to reduce the friction incident to the bed travel.

It is the purpose of my invention to provide mechanism for producing illustrations from the printing plates 3 which shall be better than prints which can be made from like plates by presses hitherto devised. My press is particularly designed for producing artistic prints; but it can be used advantageously to reproduce ordinary type matter. For the purpose of making prints from the plate 3 I provide a lower cylinder 10 and an upper cylinder 20. They are mounted for rotation in sliding journal boxes 11 and 21, respectively, by means of journals 12 and 22. The sliding boxes are carried in the superstructure *a* of the press-frame which comprises a series of standards *a*¹, *a*² and *a*³ on each side thereof. The lower cylinder 10, which I shall call the "transfer cylinder" is suitably driven by mechanism hereinafter described, so that it makes two revolutions for every reciprocation of the type bed. It carries a gear 13, which meshes with a similar gear 23 on the upper cylinder 20, hereinafter to be called the "impression cylinder", and thereby drives it at the same speed, *i.e.*, two revolutions for each reciprocation of the type bed. Means which I shall later describe in detail are provided for lowering the transfer roll into contact with the type for the purpose of making an impression in ink on the transfer roll, and other means are provided for feeding paper at the proper time to the inked transfer cylinder. The impression cylinder serves to

force the paper against the transfer cylinder with pressure sufficient to transfer the ink to the paper. For raising and lowering the transfer cylinder, a pair of vertical draw rods 11^a is provided on each side of the press. They extend from the lower part of the frame to the top of the transfer cylinder box, and the upper portions 11^b, which enter the box, are reduced to provide shoulders 11^c. Thus by means of nuts arranged at the threaded ends of the rods the box parts are secured together. The lower ends of the rods are tied together by a cross bar or strap 11^d which is adjustably secured thereto by lock nuts 11^e. It is obvious that by depressing the strap 11^d, which is secured to the rods 11^a, the box 11 carrying the transfer cylinder will be lowered. For this purpose eccentrics 11^f are provided which are mounted upon a cross shaft 11^g, and since it is necessary to lower the cylinder at a definite time, a suitably constructed cam 11^h is provided for rocking the eccentric shaft 11^g. The cam 11^h is driven from the pinion 11ⁱ on the main power shaft 11^j of the machine, which power shaft is driven from any suitable source of power, such as the belt and pulley 11^k. As it is desirable to prevent the transfer cylinder at certain times from contacting the printing plates as they move thereunder, as, for instance, when the press is being made ready, suitable means are interposed between the cam 11^h and the eccentric shaft 11^g to interrupt the regular operation thereof. It comprises a latch 11^l which normally engages a lug 11^m, fixed to the eccentric shaft 11^g, so that as the latch 11^l is moved back and forth by the cam the eccentric shaft is rocked. To interrupt the regular operation the latch 11^l is raised from engagement with the lug 11^m by means of a lever 11ⁿ. The lever 11ⁿ is mounted upon a rock shaft 11° which is operated by a foot lever 11^p arranged in position convenient to the pressman when feeding. The operative connection between the foot lever and rock shaft consists of a bell crank 11^q, link 11^r and lever 11^s. Therefore to prevent the depression of the transfer cylinder during regular operation of bed it is but necessary to press the foot lever 11^p. The mechanism thus far described is for the purpose only of lowering or depressing the cylinder and for the purpose of raising the same and holding it up when raised other means are provided. The means consist of strong springs 11 which are interposed between the lower side of the sliding box 11 and an adjustable block 11^t, through which the rods 11^a freely slide. There are many suitable well known mechanisms for raising and lowering printing cylinders and I do not limit myself to or claim specifically the means shown.

Having described means for raising and

lowering the transfer cylinder, I shall now describe the means for moving the impression cylinder to and from the transfer cylinder. It will be noticed that I have mounted the boxes 21 of the impression cylinder at an angle of substantially 45° . I do this for several reasons, one of which is that it brings the impression cylinder at a more convenient height than it would to place it directly above the transfer cylinder and at the same time it allows sufficient space for access to the type bed below it. Another reason for arranging it in this manner is that movement back and forth along a single line serves to contact it with the transfer cylinder when down, and when pulled away raises it up sufficiently to pick up the paper, when feeding, in the best manner. For the purpose of lowering the impression cylinder I provide pairs of shouldered draw rods 21^a which extend through the boxes 21. A cross strap 21^b is adjustably secured to the free ends of the rods 21^a and an eccentric 21^d mounted on a stud shaft 21^c serves to depress the strap and the box carrying the impression cylinder therewith. Since the impression cylinder must also be timed with the bed and transfer cylinder, I provide a suitably designed cam 21^e for operating the eccentric shaft 21^c. It contains a cam groove 21^f into which a cam roller on the lever 21^g enters. The cam 21^e is mounted on the shaft 11^h which carries the cam 11ⁱ, but is arranged at the opposite side of the machine. A cross shaft 21^g extending from side to side of the press is rocked from the cam 21^e through levers 21^k and 21^l. It is provided on each side with arms 21^m which, through the medium of connecting rods 21ⁿ and rock arms 21^p on the stud shaft 21^c, serve to communicate the rocking motion of the cross shaft 21^g to the eccentrics 21^d and thereby depress the impression cylinder. The impression cylinder is raised and maintained in a raised position by strong springs 21^r which are interposed between the lower side of the split box 21, and an adjustable plate 21^s through which the draw rods 21^a freely slide. In order that the movement of the impression cylinder may be accurately regulated, an adjustable block 21^u is provided for regulating the throw of the arm 21^l, and consequently the movement of the cylinder actuating eccentrics. The movement of the cylinder may also be regulated by the right and left threaded connecting rods 21ⁿ. While the impression cylinder and the transfer cylinder are moved from one another, their gears 18 and 23 are always in mesh, the amount of separation required being so slight that this can be safely accomplished. The lower or transfer cylinder is driven through a train of gearing 10^a from the power shaft 11^h. The type bed 2 is also driven from the power shaft 11^h through gearing 2^b and 2^c. One of the gears 2^c engages a rack 2^d arranged on the lower side of the type bed to drive the same in one direction and they are shifted by means (not shown) to engage the other with a lower rack 2^e to drive it in the opposite direction. Printing-press-bed reciprocating mechanism is so well known that a detailed description of it is deemed unnecessary.

It is desirable at times to prevent the impression cylinder from contacting the transfer cylinder as when the press is being made ready or when the pressman misses feeding a sheet. For this purpose I provide an arm 21^p on the rock shaft 11^m which carries a roller 21^g engaging the connecting link 21^k. It will be noticed that the operative connection between the arm 21^p and the link 21^k is by a slot-and-pin connection 21^u. Thus when the shaft 11^m is rocked by foot lever the arm 21^p swings upward and raises the end of the lever so that the slot is free of the pin. The lever then moves back and forth without rocking the shaft. It is obvious that the impression cylinder will remain in its upper position being so held by the springs 21^r. To establish regular operation the lever 21^k is merely lowered to engage the pin on the arm 21^p.

Having thus described the general operation of the machine, I shall now describe the operation, relative movements of the parts, and their unique coöperation, more in detail. This can be best done by reference to the diagrammatic views (Figs. 5 to 8 inclusive). Fig. 5 shows the type bed in the extreme rear position starting forward; Fig. 6 shows the type bed partially under the transfer cylinder with the transfer cylinder contacting the type; at which time the impression cylinder has picked up the paper. Fig. 7 shows the type-bed still transferring ink to the transfer cylinder and the impression cylinder pressing the paper against the inked transfer cylinder; and Fig. 8 illustrates the type-bed returning to the rear position and shows the transfer cylinder raised therefrom and the impression cylinder discharging the printed sheet.

In high-grade art printing no amount of labor and skill are spared in producing the best possible results. Consider, for instance, the production of illustrations from a half tone plate used in ordinary commercial work. Such a plate is often defective in tone, shading or form, and hence the reproductions struck therefrom are also defective. Even though the half tone plate be an exceptionally good one the practical difficulties encountered in producing prints therefrom by presses hitherto devised require great skill and ingenuity to retain the good qualities of the plate in the print. Further, in many instances it is impossible to print from half tone plates on certain

stock, such as matted or rough stock and secure a faithful facsimile of the picture in the plate. By the unique construction, arrangement and manipulation of the printing plates, the transfer cylinder, and the impression cylinder, I am able to produce from a given plate a print which shall retain all the good qualities of the printing plate; and further, to do this with little labor. I am able to print on rough or matted stock with as much ease as upon calendered stock. When necessary I modify or change certain tone values of the plate in order that such tone, shading and form may be produced in the print as to effect an extremely artistic print. A more full and complete description of the manner of accomplishing this is given in my companion application filed of even date herewith entitled Process of producing illustrations. Suffice it to say here that to secure this effect it is necessary to move the transfer cylinder accurately into the ink on the printing plates to pick up only so much as is necessary to approximate the desired effect in the print and to press the paper, by means of the impression cylinder, against the transfer cylinder with proper distributed pressure to select from the transfer cylinder just the proper amount of ink in the proper place. Thus in the shadows greater pressure is required than in the high lights in order that the proper amount of ink may be transferred from the plate to these parts. Practically, it is impossible to produce such variable pressure between the paper and printing plate as to pick up exactly the amount of ink required upon the different parts of the print to effect an artistic picture. Hence presses hitherto designed are defective for this reason, and so I provide mechanism whereby a variable or ink selective relation is secured between the transfer cylinder and the type and a selective pressure between the paper and the transfer cylinder. In this manner, I am able to select as near as possible so much of the ink from the printing plate and transfer it to the transfer cylinder as is necessary to approximate the distribution of ink desired in the resulting print, and then further to select so much of the ink from the transfer cylinder to effect just the desired distribution of ink in the finished print. The movement of the transfer cylinder into the ink of the printing plates shall be termed, "moving the transfer cylinder into ink selecting relation to the printing plates." The variable pressure which is secured between the paper and transfer cylinder, shall be hereinafter referred to as "selective pressure."

The transfer cylinder 10 comprises end portions or rolling surface 30 and an intermediate depressed portion 31. The end portions 30 are type high, that is, they are

in the same plane as the top of the type when the cylinder contacts the bearing parts 40 of the type frame. It is therefore necessary to build up the intermediate portion to type height. For this purpose I stretch several layers of make-ready paper over the cylinder. This I suitably secure at one end 32 to the cylinder and at the other end attach it to paper reels 33. Over the paper I stretch a sheet of thin yielding and compressible material 35 which brings the intermediate portion to "type height." A good grade of dental rubber serves well for this purpose, but other suitable yielding material may be used. Hence the term "rubber" as here used shall be construed in broad sense of any suitable yielding material. I interpose relief plates or undulators 36 between the rubber 35 and the make-ready paper. These are made with relief surfaces where the relatively heavier tones of the picture are to appear and with depressed portions where the lighter tones are to appear. It will be obvious that stretching the rubber over these relief plates will cause it to conform substantially to the undulations thereof.

When the transfer cylinder is brought into contact with the ink of the printing plates, the selective action therebetween will correspond or be proportionate to the undulations of the relief plate. Further, since the relief plate is separated from the printing plate merely by a thin single sheet of rubber, I am able accurately to control the placing of the relief plates so that they will meet the printing plate just where necessary to select the proper amount of ink. Since ink more readily adheres to rubber than it does to paper, I am able to transfer the ink with less pressure than is necessary in the flat bed presses now generally used wherein the ink is transferred from the printing plate directly to paper. While in some instances, I am able to select the ink from the printing plate so accurately that further selection is unnecessary, I can generally improve the same by again selecting the ink from the transfer roll. This I do by pressing paper against the impression cylinder, with pressure of different predetermined intensity throughout different areas. The impression cylinder also has bearing portions 40' and an intermediate depressed portion 41. The depressed portion 41 has several sheets of make-ready paper stretched thereover, paper reels 42 being provided properly to stretch the same. This cylinder is covered with a rubber blanket 43, rigidly secured at one end 47, and attached at the other end to a reel 48 whereby same can be tightly stretched. Relief plates or undulators 50 are interposed between the rubber and the paper, being usually pasted to the make-ready paper. They are arranged to register with the undulators 36 of the trans-

fer cylinder. The plates 50 are slightly different in form from the plates 36, the relief surface thereof departing therefrom in manner necessary to increase, maintain or reduce pressure where required. The relief plates 36 and 50 are not a part of the printing press in the sense that one set is used for all time, because a new set is provided for every set of printing plates. Or, in other words, each job would have a set of relief plates made for that purpose.

The operation of the press is as follows: The type bed carrying the printing plate moves from the front position (shown in Figs. 1, 2 and 5) toward the rear and in so doing the printing plates are inked. As the printing plates approach the transfer cylinder, it is lowered to contact therewith as shown in 6. The impression cylinder carries paper-feeding mechanism 60, the finger 61 of which operates to pick up a sheet of paper as it passes the feeding-board 62. The impression cylinder carrying the paper is then brought into contact with the inked transfer cylinder as shown in Fig. 7. After all of the inked surface of the transfer cylinder has passed the transfer point the impression cylinder is slightly raised; the sheet at this time is discharging as shown in Fig. 8. The transfer cylinder is also raised to permit the type bed to return without contacting it.

I do not limit myself to the specific construction herein shown and described.

Having thus described my invention, I claim as new and desire to secure by Letters Patent:

1. A printing press having a reciprocating type bed, in combination with a transfer cylinder mounted over said bed, means automatically operable for raising and lowering said transfer cylinder, an impression cylinder operatively connected to and rotating with said transfer cylinder, and automatically-operable means for moving the impression cylinder to and from the transfer cylinder.

2. In a printing press of the class mentioned, a reciprocating type bed, means for inking the type, a two revolution transfer cylinder mounted over the type bed, a two revolution impression cylinder mounted over the type bed, in combination with means for moving the transfer cylinder into ink selecting relation to the type, and means for pressing the impression cylinder against the transfer cylinder.

3. In a printing press, a reciprocating flat type bed, means for inking the type, an undulatory surfaced transfer cylinder mounted over said type bed, an undulatory surfaced impression cylinder operatively connected to rotate with said transfer cylinder, in combination with automatically operable means for raising and lowering the transfer cylinder.

der to contact the type and to clear same, and automatically operable means for moving the impression cylinder to and from the transfer cylinder.

4. In a printing press of the class described, the combination of a reciprocating flat type bed, a transfer cylinder mounted over said type bed, a rubber sheet stretched over the transfer cylinder, means interposed between the rubber sheet and the cylinder forming a variable height relief surface thereof, an impression cylinder operatively connected to rotate with the transfer cylinder, means for contacting the transfer cylinder with the inked type, and automatically operable means for contacting the impression cylinder with the transfer cylinder, as and for the purpose specified.

5. In a printing press of the class described, the combination of a reciprocating flat type bed, a transfer cylinder mounted over said type bed, a rubber covering stretched over the transfer cylinder, means interposed between the rubber covering and the cylinder forming a variable height relief surface thereof, an impression cylinder operatively connected to rotate with the transfer cylinder; a rubber covering stretched over the impression cylinder, means interposed between the rubber and the cylinder, automatically operable means for pressing the transfer cylinder against the type, and automatically operable means for pressing the impression cylinder against the transfer cylinder.

6. In a printing press of the class mentioned, the combination of a reciprocating type bed, a two revolution transfer cylinder mounted thereover, a rubber covering stretched on said transfer cylinder, means interposed between the cylinder and the rubber for raising portions thereof, in combination with a two revolution impression cylinder operatively connected to said transfer cylinder, means for depressing the transfer cylinder to take ink, and means for presenting paper to the transfer cylinder under selective pressure.

7. In a printing press of the class mentioned, a flat type bed, means for reciprocating it, a yielding surface transfer cylinder mounted over the type bed, means for rotating the same twice for every reciprocation of the type bed, a like rotating impression cylinder operated from said transfer cylinder, means for depressing the transfer cylinder to contact the type, and means for moving the impression cylinder to and from the transfer cylinder as and for the purpose specified.

8. In a printing press of the class described a flat type bed, means for reciprocating it, a transfer cylinder mounted thereover, means for rotating same twice for every reciprocation of the type bed, a like

- rotating impression cylinder operated from said transfer cylinder, a covering of yieldable material stretched over each said transfer cylinder and impression cylinder, means interposed between the covers and cylinder body of the transfer cylinder and impression cylinder for raising certain portions thereof, means for lowering the transfer cylinder, and means for moving the impression cylinder to and from the transfer cylinder.
9. In a printing press of the class described, the combination of a reciprocating flat type bed, an undulatory transfer cylinder mounted over said type bed, an undulatory impression cylinder mounted over said type bed and operatively connected for rotation with said transfer cylinder, means for depressing the transfer cylinder to pick up ink from the type when moving in one direction, means for moving the impression cylinder toward the transfer cylinder to present paper thereto, subsequent to a contact of the transfer cylinder with the type, and means operable to raise the transfer cylinder to permit the free return of the type bed.
10. In a printing press, the combination of a reciprocating type bed, a transfer cylinder mounted over the same in vertically sliding boxes, an impression cylinder mounted in diagonally sliding boxes and operatively connected to the transfer cylinder, means operable to contact the transfer cylinder with the type, means operable to contact the impression cylinder with the transfer cylinder subsequent to its engagement with the type, mechanism operable to separate the impression cylinder from the transfer cylinder, and mechanism operable to raise the transfer cylinder to clear the type when moving in one direction.
11. In a printing press of the class mentioned, a reciprocating type bed, a transfer cylinder mounted above said type bed, paper fastening and reeling means on said cylinder for stretching paper thereon, a plurality of relief members mounted on said paper to coincide with predetermined portions of the printing plates on the type bed, a yielding blanket over said relief member fixed at one end to the cylinder and wound upon a reel at the other end, an impression cylinder operatively connected to said transfer cylinder and means for automatically moving said transfer cylinder into engagement with the type and the impression cylinder into engagement with the transfer cylinder.
12. In a printing press of the class mentioned, a reciprocating type bed, a transfer cylinder mounted above said type bed, paper fastening and reeling means on said cylinder for stretching paper thereon, a plurality of relief members mounted on said paper to coincide with predetermined portions of the printing plates on the type bed,
- a yielding blanket over said relief member fixed at one end to the cylinder and wound upon a reel at the other end, a two-revolution impression cylinder operatively connected to said transfer cylinder, and a blanket of yielding material stretched thereon and adapted for the interposition of relief plates between it and the cylinder.
13. In a printing press of the class mentioned, the combination of a reciprocating type bed, a yielding undulatory blanketed transfer cylinder mounted over said type bed, mechanism operable to press the cylinder downward to contact the printing plate when moving in one direction, an impression cylinder geared to rotate with said transfer cylinder, paper pick-up mechanism on said impression cylinder, mechanism operating to move said impression cylinder toward the transfer cylinder after the transfer cylinder has taken ink from the printing plate and after the impression cylinder has picked up the paper.
14. In a printing press of the class described, the combination of a flat reciprocating bed, adapted for adjustable arrangement of printing plates thereon, means for inking the printing plates, in combination with a yielding surfaced transfer cylinder mounted over said bed, mechanism operable to press said transfer cylinder against the type as it moves thereunder in one direction, a yielding surfaced impression cylinder operatively connected to rotate with said transfer cylinder, paper-pick-up mechanism on said impression cylinder, and mechanism operable to move the impression cylinder toward the transfer cylinder after the operation of said paper-pick-up mechanism and to retract same after printing period.
15. In a printing press of the class mentioned, the combination of a reciprocating type bed, a transfer cylinder rotatably mounted thereover, an impression cylinder operatively connected to said transfer cylinder, mechanism for raising and lowering said transfer cylinder, mechanism for moving said impression cylinder to and from the transfer cylinder and mechanism operable to prevent depression of the transfer cylinder and movement of the impression cylinder toward the transfer cylinder.
16. In a printing press, the combination of a reciprocating type bed, an ink selecting transfer roll rotatably mounted thereover, an impression cylinder rotatably operable with said transfer cylinder, mechanism for moving the transfer cylinder to and from the type bed, mechanism for moving the impression cylinder to and from the transfer cylinder, and mechanism operable to throw out said transfer and impression cylinder moving mechanism.
17. In a printing press, the combination of a reciprocating type bed, an ink select-

- ing transfer roll rotatably mounted there-
over, a selective pressure impression cylin-
der rotatably operable with said transfer
cylinder, mechanism for moving the trans-
fer cylinder to and from the type bed, mech-
anism for moving the impression cylinder to
and from the transfer cylinder, and mech-
anism operable to throw out said transfer and
impression cylinder moving mechanism.
18. In a printing press, the combination
of a reciprocating flat type-bed, a yielding
surfaced ink selecting transfer cylinder ro-
tatably mounted over said type-bed, an im-
pression cylinder rotatably mounted over
said type-bed and operatively connected to
said transfer cylinder, mechanism for rais-
ing and lowering the transfer cylinder,
mechanism for moving the impression cyl-
inder to and from the transfer cylinder,
and mechanism operable to prevent depres-
sion of the transfer cylinder and movement
of the impression cylinder to and from the
transfer cylinder.

19. In a printing press, the combination
of a reciprocating flat type-bed, a yielding 25
surfaced ink selecting transfer cylinder ro-
tatably mounted over said type bed, a yield-
ing surfaced selective pressure impression
cylinder rotatably mounted over said type-
bed and operatively connected to said trans- 30
fer cylinder, mechanism for raising and
lowering the transfer cylinder, mechanism
for moving the impression cylinder to and
from the transfer cylinder, and mechanism
operable to prevent depression of the trans- 35
fer cylinder and movement of the impres-
sion cylinder to and from the transfer cylin-
der.

In testimony whereof, I have hereunto set
my hand, this 16th day of May, 1912, in 40
the presence of two subscribing witnesses.

THEODOR WENSEL.
